UNITED STATES PATENT OFFICE.

FREDERICK DARLINGTON, OF PITTSBURG, PENNSYLVANIA, ASSIGNOR TO WESTINGHOUSE ELECTRIC & MANUFACTURING COMPANY, A CORPORATION OF PENNSYLVANIA.

MOVABLE TERMINAL FOR VOLTAGE-REGULATORS.

No. 220,926.

Specification of Letters Patent.

Patented May 11, 1909.

Application filed March 8, 1906. Serial No. 304,065.

To all whom it may concern:

Be it known that I, FREDERICK DARLINGTON, a citizen of the United States, and a resident of Pittsburgh, in the county of Allegheny and State of Pennsylvania, have invented a new and useful Improvement in Movable Terminals for Voltage-Regulators, of which the following is a specification.

My invention relates to voltage regulators and particularly to regulators of the class in which voltage variations are effected by varying the active lengths of transformer windings.

The object of my invention is to provide a novel and improved structure for the movable contact members of such regulators whereby voltage variation may be effected in circuits that are traversed by large amounts of current without injury to the engaging parts by either burning or abrasion.

In the construction and use of all forms of switches, it has been found that the amount of current which may be effectively conducted between the stationary and movable contact members, may be increased materially by causing the members to engage each other under heavy pressure. It has also been found desirable to cause the engaging members to rub or slide upon each other in order to maintain clean surfaces of contact, but if heavy pressure is exerted upon the parts the surfaces will wear very rapidly and thus render such an arrangement impracticable. I accordingly propose to provide the movable terminal with a plurality of cylindrical contact members of different diameters and to mount them resiliently upon a shaft so that all must rotate together. When so constructed, both rolling and sliding engagement between the movable and stationary contact members may be effected and a movable terminal is provided which has a very high current carrying capacity and but little friction and insures clean surfaces of contact.

Figure 1 of the accompanying drawing is a view, in side elevation of a voltage regulator that embodies my invention. Fig. 2 is a plan view of the movable contact member of the voltage regulator shown in Fig. 1 and Fig. 3 is a view, in side elevation, of a portion of the movable contact member of the regulator.

I have found it convenient to apply my invention to a voltage regulator that forms

the subject-matter of another application, Serial No. 304,064, filed by me of even date herewith, such a regulator comprising a magnetizable core 1, and windings 2 and 3, that are intercoiled or otherwise juxtaposed upon the core, in a manner similar to a double threaded screw, so that faces of the respective windings are exposed alternately as contact surfaces with which a movable terminal member 4, that may be connected to any device to which it is desired to supply variable voltages, is adapted to engage. The corresponding pairs of terminals of the windings 2 and 3 are connected by means of resistances 5 and 6, connections from an external circuit (not shown) being made to the middle points 7 and 8, or to other points intermediate the terminals thereof.

The terminal member 4 comprises a frame 9 and a plurality of contact rings or wheels 10, 11, 12 and 13 that differ slightly in diameter and are resiliently mounted and secured by any suitable means, such as springs 14 and screws 14^a or other fastening devices, upon a shaft or spindle 15, that has bearings 80 in the frame 9; all of the rings being in this manner compelled to rotate at the same speed. The movable terminal may be operated by means of a screw-threaded shaft 16 that may be rotated by any suitable motor, and it should either be of great weight itself or pressure should be applied to it in some convenient manner.

It will be readily understood that, because of the resilient mountings, all of the contact rings 10 to 13 inclusive will engage the exposed faces of the windings 2 and 3, and because they differ in diameter, both sliding and rolling engagement will occur, when the member is moved over the windings 2 and 3. When the terminal member is thus constructed and arranged, the engaging surfaces of the stationary and movable members will be kept fresh and clean, while the current density at the engaging faces may be very high and the mechanical dimensions of the movable terminal member may be correspondingly small. The friction in operation is also very small because of the comparatively small amount of sliding between the parts.

In the operation of the voltage regulator the movable terminal connects first to one winding, next to both of them and then to the other, the cycle being repeated as many

times as may be necessary to effect the desired regulation. When the movable member connects to both windings, local circuits are established through the windings but the voltages of such circuits will be small. The amounts of current in the local circuits will also be limited, since the whole of the resistances 5 and 6 are then included in the circuits. When the movable terminal engages 10 but one of the windings, only one-half of each resistance is in circuit.

While I have shown and described my invention as applied to a specific form of regulator, it will be readily understood that it is 15 not limited in its application to such specific use, but may be employed in connection with other forms of voltage regulators and in connection with other devices. The number of contact members may obviously be 20 varied from what has here been shown and described and the structural details and arrangements of parts may also be varied considerably without modifying the mode of 25 operation of the invention or departing from its spirit.

I claim as my invention:

1. The combination with one or more stationary contact terminals, of a coöperating movable circuit terminal comprising a plurality of side-by-side contact members that may have relative movement toward and away from the stationary contact terminal or terminals but only conjoint rotative movement.

35 2. The combination with one or more stationary contact terminals, of a coöperating

movable circuit terminal comprising a plurality of side-by-side rotatably mounted contact members of the same form but of different diameters.

3. The combination with one or more stationary contact terminals, of a coöperating movable circuit terminal comprising a plurality of side-by-side resiliently and rotatably mounted contact members of the same 45 form but of different diameters.

4. The combination with one or more stationary contact terminals, of a coöperating movable circuit terminal comprising a plurality of contact rings of different diameters 50 55 resiliently mounted upon a shaft to rotate at the same speed.

5. A contact terminal comprising a plurality of rings or wheels of different diameters and a shaft upon which said rings or 55 wheels are yieldingly but non-rotatively mounted.

6. A contact member for electrical apparatus comprising a plurality of rings or 60 wheels of different diameters, a rotatable shaft and spring connections between the rings or wheels and the shaft which permit relative lateral movement but preclude relative rotary movement.

In testimony whereof, I have hereunto 65 subscribed my name this 21st day of February, 1906.

FREDERICK DARLINGTON.
